UNITED STATES PATENT OFFICE.

DAVID LEONARD HAMPTON, OF FORT WORTH, TEXAS.

HEATING AND VENTILATING SYSTEM.

Application filed November 9, 1923. Serial No. 673,784.

To all whom it may concern:

Be it known that DAVID LEONARD HAMPTON, a citizen of the United States, residing at Fort Worth, in the county of Tarrant and State of Texas, has invented certain new and useful Improvements in Heating and Ventilating Systems, of which the following is a specification.

This invention pertains to heating and ventilating systems, and the object is to provide a relatively simple, practical and efficient system of this character for heating and ventilating buildings of various kinds.

In the drawing the figure is a side elevation of the assembled apparatus.

The invention includes a main air pipe 1 mounted horizontally through the building which is to be equipped, and having in one end thereof a draft fan 2 for forcing air through the pipe. A hot air pipe 3 branches from the pipe 1 and is extended to the furnace or heater. A draft fan 4 is likewise mounted in the pipe 3 to force air therethrough. Dampers 5 and 6 are mounted in the pipes 1 and 3 respectively. Blowers 7 and 8 are mounted at intervals along the pipe 1, as desired, with their mouths 9 and 10 opening into the rooms above. Hot air pipes 11 and 12 branch out from the main pipe 1 and connect with the blowers. Dampers 13 and 14 are mounted in these branch pipes. A cold air pipe 15 is extended to a refrigerating plant and branch pipes 16 and 17 lead from this pipe 15 into the blowers. A damper 18 is provided for the cold air pipe 15. The operation of the apparatus is as follows: Under a normal outside temperature which were neither too hot nor too cold, the main pipe 1 would be left open, the dampers 5, 13 and 14 being opened, and the dampers 6, and 18 being closed. The fan 2 is then operated for

forcing air of normal temperature into and through the pipes 1, 11 and 12 into the rooms above through the mouths 9 and 10 of the blowers 7 and 8 with which the pipes 11 and 12 are connected. In cold weather and in order to supply warm air, the dampers 5 and 18 would be closed, the dampers 6, 13 and 14 opened, and the fan 4 operated. In warm weather and in order to supply cool air, the dampers 5 and 6 would be closed and the dampers 13, 14 and 18 opened, the blowers 7 and 8 then forcing the cool air into the rooms. The blowers 7 and 8 would run continuously under all conditions.

While I have herein described a certain specific manner and method of constructing and assembling the elements of my invention, it is understood that I may vary from the same in minor details, not departing from the spirit of my invention, so as best to construct a practical device for the purpose intended, as defined in the appended claim.

I claim:

An apparatus of the kind described, comprising a main air pipe horizontally extended; a hot air pipe extended from the main pipe; draft fans and dampers mounted in the main pipe and the hot air pipe; blowers mounted along the main pipe; branch hot air pipes connecting the main pipe with the blowers; dampers in the branch hot air pipes; a cold air pipe; and branch cold air pipes connecting the cold air pipe with the blowers.

In testimony whereof I affix my signature.

DAVID LEONARD HAMPTON.
